FRANK D. VOGLER, OF MILWAUKIE, OREGON

MEANS FOR AERATING THE UNDERSKIN OF VESSELS AUTOMATICALLY

Application filed April 24, 1930. Serial No. 446,945.

My invention is intended for use upon boats and has for its object the admitting of air across the bottom strakes of the boat and especially along the stern portion of the bottom of the boat in order to lessen the frictional resistance of the boat with the water when traveling at relatively high speed.

The invention consists primarily of means placed at one or more points for the admitting of air along, or across the entire rearward bottom portion of the boat to lessen the frictional resistance between the bottom skin of the boat and the water over which the same travels. Fins are further provided to prevent eddies forming at the sides of the boat caused by the air flowing athwart the boat. The fins maintain the air currents in stream line and prevent the air to escape sidewise of the boat, but confines the same in stream-like lines for the after portion of the bottom of the boat.

One of the objects of my invention is to increase the speed of relatively high speed boats.

A further object of my invention is to lessen the fuel required in the propelling of high speed boats.

A still further object of my invention consists in providing automatic means for preventing the surge encountered in high speed boats from entering the hull of the boat through the air passages when the power is shut off.

A still further object of my invention resides in providing means for the distribution of air over the bottom skin of the boat.

With these and incidental objects in view, the invention consists in certain novel features of construction and combination of parts, the essential elements of which are set forth in the appended claims, and a preferred form of embodiment of which is hereinafter shown with reference to the drawings which accompany and form a part of this specification.

In the drawings:

Fig. 1 is a longitudinal, sectional, side view of a speed boat.

Fig. 2 is a vertical, cross sectional view taken on line 2—2 of Fig. 1, looking in the direction indicated.

Fig. 3 is an inverted plan view of the boat illustrated in Fig. 1.

Fig. 4 is a fragmentary, sectional side view of the inlet air passage extending through the bottom strakes of the boat.

Fig. 5 is a sectional, side view of a two-step air passage and illustrating funnels for admitting air into the inlets transversely disposed at the bottom strakes of the boat.

Fig. 6 is a vertical, sectional view of the boat illustrated in Fig. 5, the same being taken on line 6—6 of Fig. 5, looking in the direction indicated.

Fig. 7 is a perspective, end view of one of the cross members comprising one of the frames of the boat to which the bottom and side strakes are fastened and through which air is admitted from the funnels into the air passages.

Like reference characters refer to like parts throughout the several views.

I provide an air inlet passage 1 disposed entirely across the bottom strakes of high speed boats and arrange the bottom strakes 2 and 3 in spaced relationship with each other to provide an outlet passage 4 for the air to pass therethrough and along the bottom stern portion of the bottom strakes. A closure 5 is provided for the closing of the inlet passage 1. I have found that greater speed is obtained and less disturbance to the water occurs if the boat has parallelly disposed fins 6 extending rearwardly from the inlet passage and uniformly taper from a relatively thin edge in the rear and to substantially the full depth of the spaced relationship including the depth of the forward strakes as illustrated at 7 in Fig. 2. In boats of longer length, it may be necessary to place the inlet

passageways 8 and 9 as illustrated in Fig. 5 and have a set of tapered fins 10 disposed between the two inlet passages and a rear set of spaced fins 11 extending from the rear or stern air inlet 8 and extending substantially to the stern 12 of the boat. I have also observed that the air may be admitted into the passageways under substantial pressure by the placing of funnels 13 and 14 disposed at either side of the boat and having a plurality of separator blades 15 and 16 disposed within the passageway 17. The ends of the separator blades terminate between the respective spaced fins in order to uniformly distribute the air under substantial pressure through the inlet passages and over that portion of the skin of the boat disposed rearwardly of the step or steps of the boat through which the air is discharged. Cross frames may be made substantially as illustrated in Fig. 7 wherein the side strakes of the boat may be secured to flanges 18 and 19 disposed at either side of each end of the frame. Outwardly extending flanges are disposed at the bottom at 20 to which the bottom strakes are secured with separator blades 15 and 17 disposed between the side walls 22 and 24 of the frame with a funnel disposed at the upper end thereof for conducting the air into the passageways. The distributor blades distribute the air over the entire rear bottom portion of the boat. I have observed that the admitting of the air under substantial pressure also adds somewhat to the high speed of relatively high speed boats. Automatic means may be made for preventing the back surge of the water from entering the boat. The automatic means consists of the mechanism illustrated in Fig. 4 wherein vertically disposed walls 26 and 27 upwardly extend from the boat strakes and a hinged closure 28 is hingedly secured to one of the walls by any suitable hinging means 29. A counterbalanced weight 30 is secured to the closure 28 and normally maintains the passageway 31 closed. When a suction is created within the passageway by an already obtained relatively high speed, the draft created upon the closure 28 draws the same down about the hinge, thus permitting a free entry of air into the passageway. As soon as the pressure is released the counterweight 30 closes the same.

While the form of mechanism herein shown and described is admirably adapted to fulfill the objects primarily stated, it is to be understood that it is not intended to confine the invention to the one form of embodiment herein shown and described, as it is susceptible of embodiment in various forms, all coming within the scope of the claims which follow.

What I claim is:

In a device of the class described, the combination of a boat hull, the bottom strakes of the hull being cut and disposed in spaced relation with each other to form a step for

the full width of the bottom strakes, an inlet passage disposed across the boat bottom for the admission of air across the bottom strakes of the boat, tapered fins parallelly disposed in spaced relation with each other and secured to the bottom strakes and running longitudinally of the boat, and a counter balanced air controlled valve disposed in line with the inlet passageway.
